UNITED STATES PATENT OFFICE.

CHARLES BOWNE CARR, OF NEW YORK, N. Y.

EYE-WIPER.

1,305,442.

Specification of Letters Patent.

Patented June 3, 1919.

Application filed June 14, 1918. Serial No. 240,078.

To all whom it may concern:

Be it known that I, CHARLES BOWNE CARR, a citizen of the United States, and resident of New York city, in the county of New York and State of New York, have invented certain new and useful Eye-Wipers, of which the following is a specification.

This invention relates to a device for removing from the eye small particles of dust, sand, cinders or the like which may have been lodged therein, or embedded in the membrane thereof.

The invention has for an object to provide a simple and inexpensive device whereby 15 cinders, said, grit or other foreign matter which may have become lodged in the eye may be readily removed.

A further object is to provide a device by which such foreign substance may be easily 20 removed by the person in whose eye it may have become lodged or embedded without requiring the employment of a mirror or the like to locate the substance.

A still further object of my invention is to 25 provide a device of this kind which may be readily carried in the pocket or in purses, hand bags or the like.

For further comprehension of the invention, and of the objects and advantages 30 thereof, reference will be had to the following descriptions and accompanying drawings, and to the appended claims in which the various novel features of the invention are more particularly set forth.

Figure 1 of the drawings is a side elevation 35 of the device with its protecting cap in place.

Fig. 2 is a similar view with the protecting cap removed.

Fig. 3 is a view, partly in elevation and 40 partly in vertical section at right angles to Fig. 2, with the cap in place.

Fig. 4 is an enlarged horizontal section on the line 4—4 of Fig. 2.

Fig. 5 is a side elevation, partly broken 45 away, of a modification.

Referring now to Figs. 1 to 4 my improved device comprises a base or handle 2 which is preferably of cylindrical shape and 50 of such a size as to be conveniently held between the thumb and fingers. This base may be of any suitable material such as hard rubber and may have a knurled exterior finish as shown.

Projecting from this base is a U-shaped 55 wire 3 whose ends are firmly secured to the

base 2, being here shown as embedded therein as indicated at 4 and 5.

Supported by the wire 3 is a comparatively thin, flat strip 6 of soft rubber which 60 may be termed a wiper. In the modification shown in Figs. 1 to 4 this strip is molded over the wire 3 and onto the base 2. The wire 3 is of resilient metal, such as steel and of very small size the wiper thus possessing 65 the necessary flexibility and resiliency to work on the eye without fear of injury to the latter.

To protect the wiper when the device is not in use I provide a cap 7 which may be 70 screwed on the threaded neck 8 formed on the base 2 or otherwise detachably secured to the latter.

In the modification shown in Fig. 5 the device has a base 2', similar to the base 2, 75 which supports a U-shaped wire 3', similar to the wire 3.

In this modification however, the wiper comprises a thin rubber tube 10, closed at one end, which is slipped over the wire 3' 80 and is held in place by having its inturned end 11 stretched over a bead 12 formed on the base 2'. The base is also provided with a threaded neck 7' for attaching a cap there- 85 to. It will be apparent that this tube when in place constitutes also, in effect, a thin, flat strip of soft rubber, the tube being of a diameter to cause it to flatten out over the wire when applied to the latter and assume the shape in cross section shown in Fig. 4. 90

In using my device it is preferable to first moisten the wiper which is then gently rubbed over the eyeball or against the inner surface of the lids.

The rubber surface coming in contact with 95 a cinder or other small particles of matter, which may have become attached to or em- bedded in the membrane of the eye or lid, will immediately dislodge the latter by rea- son of the adhesive nature of the rubber 100 which causes it to grip the cinder, this grip- ping power of the rubber being enhanced also by the flexibility of the wiper.

This device can be used without any dan- 105 ger of injury to the eye, and without any pain to the user; the delicate membranes of the eye being in no manner hurt by the pas- sage of the smooth and flexible wiper there- over.

It will be apparent also that with this de- 110 vice the necessity of locating the foreign matter by sight is obviated since the person

in whose eye it may have become lodged may remove it by simply passing the wiper over the portion of the eye and lid where the irritation is felt.

5 My improved device is simple in construction and may be cheaply manufactured, while it may be readily carried around in the pocket, or otherwise, by the prospective user.

10 It will be apparent that various other changes and modifications may be made than that herein shown without departing from the spirit of the invention and the right is reserved to all changes and modifications 15 coming within the scope of the appended claims.

What I claim as new and desire to secure by Letters Patent is as follows:

1. A device of the class described, comprising a wiper composed of a comparatively thin strip of soft rubber and a resilient stiffening wire molded within and extending entirely around the lateral edges of said strip near the periphery thereof.

25 2. A device of the class described comprising a wiper composed of a comparatively thin strip of soft rubber, and a U shaped wire forming a stiffening device molded within and extending lengthwise of said strip within the latter and near opposite edges thereof.

ing a wiper composed of a comparatively thin strip of soft rubber, and a U shaped wire forming a stiffening device molded within and extending lengthwise of said strip within the latter and near opposite 30 edges thereof.

3. A device of the class described comprising a rigid base having a screw-threaded end, a flexible wire loop the ends of which are secured in said screw-threaded end, a soft rubber strip molded over said loop in such manner that the wires of said loop lie adjacent the lateral edges of said strip near the periphery thereof, and a screw-threaded 35 cover adapted to engage the screw-threaded end of said base.

Signed at 63 Park Row, New York city, N. Y., in the county of New York and State of New York, this 16th day of April, A. D. 1918.

CHARLES BOWNE CARR.
